UNITED STATES PATENT OFFICE.

JOHN B. OWENS, OF ZANESVILLE, OHIO.

MULTIPLEX-TUNNEL KILN.

1,356,398.

Specification of Letters Patent. Patented Oct. 19, 1920.

Application filed February 18, 1919. Serial No. 277,718.

To all whom it may concern:

Be it known that I, JOHN B. OWENS, a citizen of the United States, residing at Zanesville, in the county of Muskingum and

5 State of Ohio, have invented certain new and useful Improvements in Multiplex-Tunnel Kilns, of which the following is a specification.

The object of the present invention is the 10 provision of a practical and efficient improved multiplex tunnel kiln wherein a plurality of trains or ware-bearing cars may concurrently progress, side by side, through the tunnel.

15 My improved tunnel kiln is intended, more particularly, for use in those situations where the clay or other product or ware is so heavy that the use of a wide car is impractical because of the difficulty attending its 20 movement and the power which would become necessary to propel a train of wide cars through the kiln.

Consequently, the kiln finds particular usefulness in those situations where the use 25 of narrow cars is necessary or advisable, although it is to be understood that I do not restrict the use of the improvements to such situations.

The present invention is adapted for use 30 on a tunnel kiln having but one firing zone, in the firing of brick and hollow tile. It is preferable, however, to use two or more firing zones, as set forth, for example, in my application Serial No. 249827, filed August 35 14, 1918.

In my present kiln, a closed partition wall extends lengthwise within the kiln, dividing the tunnel into a plurality of parallel longitudinally-extending tunnels or chambers, 40 each having its own track. If it is desired to operate two tracks and trains of cars, a single partition will be provided along the longitudinal center line of the kiln; if three tracks and trains, two partitions, providing 45 three separate parallel tunnels or compartments. The partition walls have suitable seals for the edges of the car platforms to prevent the heat from passing down below the car platforms.

50 The trains of cars, carrying the ware or clay products, travel through the tunnel in the same direction on opposite sides of the partition wall.

The length and height of the partition 55 wall or walls may vary but it is generally desirable that said wall or walls extend con-

tinuously at least from a point in the general region of the stack, through the heating zone or zones, well into, and even through to the end of, the cooling zone. 60

The partition wall or walls may extend clear up to the top arch of the kiln, or, stop short at any point below the arch. Preferably, the partition wall should extend only slightly above the level of the car platforms, with a free space thereabove. The clay products or ware on the trains in the respective tunnels being the walls of said free space, they form a flue which extends longitudinally between the car contents above

70 the car platforms the full length of the partition. This flue allows free passage of the heat between the cars from the heat zone to the stack; especially, with the partition extending from the heat zone, through the cooling zone, to the exit end of the kiln, thereby eliminating cold drafts. The heat passes freely through the flue, lengthwise

75 of the kiln, between the car contents until it is taken off, in the region of the stack, by exits or flues which causes the heat to spread from the longitudinal flue and to pass through the car contents before leaving

80 the tunnel.

80 Consequently, the kiln finds particular usefulness in those situations where the use of narrow cars is necessary or advisable, although it is to be understood that I do not restrict the use of the improvements to such situations.

85 The present invention is adapted for use on a tunnel kiln having but one firing zone, in the firing of brick and hollow tile. It is preferable, however, to use two or more firing zones, as set forth, for example, in my application Serial No. 249827, filed August 14, 1918.

90 In my present kiln, a closed partition wall extends lengthwise within the kiln, dividing the tunnel into a plurality of parallel longitudinally-extending tunnels or chambers, each having its own track. If it is desired to operate two tracks and trains of cars, a single partition will be provided along the longitudinal center line of the kiln; if three tracks and trains, two partitions, providing three separate parallel tunnels or compartments. The partition walls have suitable seals for the edges of the car platforms to prevent the heat from passing down below the car platforms.

95 The trains of cars, carrying the ware or clay products, travel through the tunnel in the same direction on opposite sides of the partition wall.

100 In the following description, and accompanying drawings, I have disclosed certain embodiments of the invention to set forth the principle thereof; such disclosure is to be considered as illustrative, and not re-

I do not limit myself to any length or height of the partition wall or walls nor the location of their termini.

In the following description, and accompanying drawings, I have disclosed certain embodiments of the invention to set forth the principle thereof; such disclosure is to be considered as illustrative, and not re-

strictive, of the invention, as modifications may be resorted to.

In the accompanying drawings:

Figure 1 is a horizontal section, the tunnel being broken across, disclosing one form of the invention;

Fig. 2, is a perspective, showing a cross-section through one of the pairs of furnaces, and the partition wall, and also having parts of the tunnel broken away to show the construction of the partition in the region of the stack and its connections to the latter;

Fig. 3, is a vertical cross section through the kiln and the stack; and

Fig. 4, is a vertical cross section through one of the pairs of furnaces, showing a modification employing two partition walls and three compartments or subdivisions of the tunnel to accommodate three trains of cars.

My present invention may be carried out in a tunnel kiln having but one firing zone and one furnace or pair of furnaces but it is shown in the drawings as embodied in a tunnel kiln having two sets of furnaces and a multiple firing zone, as shown in my application, Ser. No. 249827, filed August 14, 1918 as the greatest efficiency of the invention is obtained when a multiple firing zone is provided, particularly when three-tracks, in three tunnels, are employed.

The preheating zone appears at 1, the multiple firing zone at 2, the multiple furnaces are shown at 3, and the cooling zone at 4. The cars bearing the ware or clay products, enter the tunnel 5 at the right hand end, Fig. 1, and emerge from the left hand end, as indicated by the arrows. The stack is shown at 6.

As in the kiln of my application, Ser. No. 249827, the furnaces are fired in the direction of their length, that is, longitudinally thereof, parallel to the kiln tunnel 5, the openings 7, 8, in each instance being for the admission of the firing means, such as a source of oil supply, and for the admission of air.

Extending longitudinally of the tunnel 5, along the median line thereof, is a partition wall 9 which subdivides the tunnel into two longitudinal chambers or compartments 10, 11, each being open the entire length of the tunnel. Each compartment has its own set of tracks 12 and in each compartment a train of cars, of any desired kind, for carrying the ware or clay products, is adapted to travel, as shown at 13 and 14, on the said tracks 12. The cars, and trains composed 60 of the cars, travel side by side in the same direction through the respective compartments or chambers 10, 11. The partition wall is closed so that, in connection with the stacks of clay products on the cars, the heat 65 and products of combustion from the fur-

nace will be compelled to travel lengthwise of the tunnel of the kiln.

The length of the partition wall 9 and the location of its termini 15, 16, may vary but, preferably, said partition wall should extend continuously from a point in the general region of the stack 6, through the heating zone or zones 2, well into the cooling zone 4, or through to the exit end of the kiln. In the drawings, the partition is shown as extending from a point somewhat in advance of the region of the stack, clear through to the exit end of the tunnel.

The partition wall 9 may be of any desired thickness, depending on conditions to be met in the particular kiln being installed. The partition will, however, be provided with suitable seals 17 for the edges of the car platforms, and the kiln walls will have similar seals 18, to prevent the heat from above the cars from having access to the space below the cars.

The partition wall may run clear up to the crown of the arch at the top of the kiln, or, it may stop short at any desired height. Preferably, the top of the partition is low down, that is, just above the level of the car platforms, as shown in the drawings. If desired, the car contents may be stacked so that they will overhang the top of the partition wall 9.

As shown, there is a free space between the ware or clay products on the adjacent trains of cars which constitutes a flue 19 whose bottom is the upper face of the partition 9, and whose sides are defined by the ware or clay products on the cars. This flue extends lengthwise of the kiln the full length of the partition and allows free passage of the heat between the cars, as it flows from the firing zone to the stack.

Exit flues 20, 21 take the heat off from the respective tunnels or chambers 10, 11 to a flue 22, leading to stack 6. Dampers 23 control the flues 20, 21 for the regulation of the draft. The flues 20, 21, communicate with the chambers or tunnels 10, 11 through the walls of the kiln, in the region of the level of the car platforms, or, at least, the region of the lower parts of the car contents. Consequently, the heat from flue 19 spreads through the clay products or ware and is drawn to the lower parts thereof, insuring thorough heat distribution.

The efficiency of the kiln is increased by the use of the partition wall 9 which insures a far greater regularity of distribution of the heat flowing from the furnaces to the ware or clay products than is possible if no partition is employed when multiple tracks and car-trains have to be used.

In Fig. 4, two partition walls 9, 9^a are shown, subdividing the tunnel into three longitudinal compartments 24, 25, 26, making provision for three parallel trains of

cars being run through the tunnel at the same time. The draft is taken off in the manner shown in Fig. 3.

My improvements permit the use of narrow cars in those situations where wide cars are impractical.

What I claim is:

1. In a tunnel kiln having a plurality of tracks extending side by side lengthwise of the kiln, cars operating on said tracks which are adapted to carry the ware or clay products through the kiln, a closed partition rising between the car platforms and extending lengthwise of the kiln between the sets of tracks, the walls of said kiln being imperforate where they face the partition, and means for sealing those parts of the tunnel which are below the cars from those parts which are above the cars, whereby the partition and the ware or clay products on the cars define a longitudinal flue in the kiln compelling the passage of the heat and products of combustion lengthwise of the tunnel of the kiln.
2. In a tunnel kiln having a plurality of tracks extending side by side lengthwise of the kiln, cars operating on said tracks which are adapted to carry the ware or clay products through the kiln, a closed partition rising between the car platforms and extending lengthwise of the kiln between the sets of tracks whose top is located below the crown of the kiln, the walls of said kiln being imperforate where they face the partition, and means for sealing those parts of the tunnel which are below the cars from those which are above the cars, whereby the partition and the ware or clay products on the cars define a longitudinal flue in the kiln compelling the passage of the heat and products of combustion lengthwise of the tunnel of the kiln.
3. A tunnel kiln provided with one or more closed partitions extending in the direction of its length, said partition or partitions subdividing the kiln into a plurality of compartments or chambers, means for conveying ware or clay products through the respective compartments or chambers, the walls of said kiln being imperforate where they face the partition or partitions, combustion chambers for delivering heat into the kiln, means for sealing those parts of the chambers or compartments below the conveying means from those parts which are located above the conveying means, and means for taking the draft off in the region of the lower parts of the ware or clay products, said ware or clay products in the tunnel defining, in connection with the partition or partitions a longitudinal flue or flues according to whether one or more partitions are provided, said flue or flues compelling the passage of the heat and products of combustion lengthwise of the tunnel of the kiln.
4. A tunnel kiln having a firing zone and a cooling zone and provided with one or more closed partitions extending in the direction of its length from a point in the firing zone to a point in the cooling zone, combustion chambers, means for conveying ware or clay products through the tunnel, means for sealing the space below the ware conveying means from the space thereabove, the ware or clay products defining in the tunnel, in connection with the partition or partitions one or more longitudinally extending flues according to the number of partitions employed, said flue or flues completing the passage of the heat and products of combustion lengthwise of the tunnel of the kiln, and means for taking the draft off in the region of the advance portion of the partition or partitions, and of the lower parts of the car contents whereby the heat and products of combustion from the combustion chambers pass between the ware and longitudinally along the flue or flues to the point of takeoff and thence through the ware to the draft takeoff.

In testimony whereof I affix my signature:

JOHN B. OWENS.
